(57) **CLAIM**

The ornamental design for a combined blade and guard, as shown and described.

DESCRIPTION

FIG. 1 is a perspective view of a combined blade and guard in accordance with the present invention;

FIG. 2 is a top view thereof;

FIG. 3 is a bottom view thereof;

FIG. 4 is a right side view thereof;

FIG. 5 is a left side view thereof;

FIG. 6 is a rear elevational view thereof; and

FIG. 7 is a front elevational view thereof.

FIG. 8 is a front perspective view of another embodiment of a blade and guard in accordance with the present invention;

FIG. 9 is a top view thereof;

FIG. 10 is a bottom view thereof;

FIG. 11 is a right side view thereof;

FIG. 12 is a left side view thereof;

FIG. 13 is a rear elevational view thereof; and,

FIG. 14 is a front elevational view thereof.

The broken lines shown in the drawings illustrate the environment for the combined blade and guard and form no part of the claimed design.
